(57) **CLAIM**

The ornamental design for a vent cover for an air purifier, as shown and described.

DESCRIPTION

FIG. 1 is a top front perspective view of a vent cover for an air purifier, showing the vent cover in an environment of use with an air purifier;

FIG. 2 is a top front perspective view of the vent cover of FIG. 1;

FIG. 3 is a bottom front perspective view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a front elevation view thereof;

FIG. 9 is a rear elevation view thereof;

FIG. 10 is an exploded top front perspective view of the vent cover of FIG. 2, showing the upper and lower portions separated for clarity of disclosure;

FIG. 11 is an exploded bottom front perspective view thereof; and,

FIG. 12 is a cross-sectional view of the vent cover taken along line 12-12 in FIG. 4.

The broken lines in the drawings show portions of the vent cover for an air purifier that form no part of the claimed design.
